(57) **CLAIM**

The ornamental design for a solution production system, as shown and described.

DESCRIPTION

FIG. 1 is a perspective view of a solution production system of the present invention.

FIG. 2 is a rear view thereof;

FIG. 3 is a front view thereof;

FIG. 4 is a left side view thereof;

FIG. 5 is a right side view thereof;

FIG. 6 is a top view thereof;

FIG. 7 is a bottom view thereof; and,

FIG. 8 is a top view of the bottom portion of the solution production system.

The broken lines represent portions of the article that form no part of the claim.
